DESIGN FOR A STAPLE HAMMER

Robert E. Barclay, Chicago, Ill., assignor to Vail
Manufacturing Company, Chicago, Ill., a cor-
poration of Illinois

Application June 15, 1945, Serial No. 120,110

Term of patent 3½ years

(Cl. D93—4)

To all whom it may concern:

Be it known that I, Robert E. Barclay, a citizen of the United States, residing at Chicago, in the county of Cook and State of Illinois, have invented a new, original, and ornamental Design for a Staple Hammer, of which the following is a specification, reference being had to the accompanying drawing, forming part thereof, wherein:

Fig. 1 is a side elevation of a staple hammer showing my new design;

Fig. 2 is a top plan view thereof; and
Figs. 3 and 4 are elevational views of the head and handle ends thereof, respectively.

I claim:

The ornamental design for a staple hammer, as shown.

ROBERT E. BARCLAY.
